CLAIM

The ornamental design for a nestable plastic container, as shown and described.

DESCRIPTION

FIG. 1 is a top, front and right side perspective view of a plastic container showing our new design;

FIG. 2 is a top, rear and left side perspective view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a front elevation view thereof;

FIG. 8 is a rear elevation view thereof;

FIG. 9 is a right side elevation view of two nested plastic containers as shown in FIG. 1, in use condition; and,

FIG. 10 is a cross sectional view taken along the line 10—10 in FIG. 7.

The broken line showing of a pour spout and bottom of the bottle is included for the purpose of illustrating only and forms no part of the claimed design.

UNITED STATES PATENT AND TRADEMARK OFFICE
CERTIFICATE OF CORRECTION

PATENT NO. : Des. 586,664 S

Page 1 of 1

APPLICATION NO. : 29/272726

DATED : February 17, 2009

INVENTOR(S) : Richard C. Darr, James J. Miller and Richard A. Lovelace, Jr.

It is certified that error appears in the above-identified patent and that said Letters Patent is hereby corrected as shown below:

On the title page, after Item (75) Inventors: "Rchard C. Darr" should be -- Richard C. Darr --

Signed and Sealed this

Thirty-first Day of March, 2009

JOHN DOLL
Acting Director of the United States Patent and Trademark Office
